UNITED STATES PATENT OFFICE.

BENJAMIN E. HERVEY, OF WALLACE, IDAHO.

LIFE-SAVING SUIT.

1,197,823.

Specification of Letters Patent. Patented Sept. 12, 1916.

Application filed March 9, 1916. Serial No. 83,156.

To all whom it may concern:

Be it known that I, BENJAMIN E. HERVEY, residing at Wallace, in the county of Shoshone and State of Idaho, have invented 5 certain new and useful Improvements in Life-Saving Suits, of which the following is a specification.

My invention relates to improvements in life saving appliances and has particular reference to that class of life saving devices in the nature of garments, especially designed for ocean traveling, and which, in an emergency can be quickly placed over the clothing usually worn.

15 In the practical development of life saving devices of the general character stated, such as have been reduced to practice, they have been more or less complicated in their structure and cumbersome, to such extent 20 that in putting them on the services of an attendant has been necessary and the closing of the separable parts effected from the outside.

My invention primarily has for its object 25 to provide a life saving outfit or suit of a simple and economical construction, which, when not in use may be packed and carried with other baggage and which when required, can be easily manipulated by the 30 user when applying the same for use, and in which the closure elements are such that locking of the separable parts is effected by the user inclosed within the suit.

Again, my invention seeks to provide a 35 life saving means of the general character stated, which, when not in use can be folded up in a compact form and when applied on the person for use serves as a container for holding the person upright in the water 40 with the head well above the water, either incased within the closed head portion or exposed, under conditions that permit of the user opening the head gear.

Again, my invention has for its object 45 to provide an improved life saving appliance or suit, of a light and durable character and such that when fitted will, when the user dives into the water, quickly bring the person contained therein, to the surface 50 in an upright position and afford sufficient use of the arms to allow such user to adjust the port hole to admit air to the interior of the suit.

Further objects of my invention will be 55 apparent in the detailed description thereof, and which consists in the peculiar com-

bination and novel arrangement of parts, hereinafter described, specifically pointed out in the appended claim and illustrated in the accompanying drawing, in which:

Figure 1 is a perspective view of my invention, the same being shown as applied for use. Fig. 2 is a vertical section thereof, the same being shown in the operative condition. Fig. 3 is a perspective view that 65 illustrates the manner of putting on the suit. Fig. 4 is a section of the upper or head gear portion and illustrates the manner in which the hinged members of the said head gear are clamped together, water 70 tight, by the user. Fig. 5 is a section on the line 5—5 of Fig. 4. Fig. 6 is a section on the line 6—6 of Fig. 2. Fig. 7 is a section on the line 7—7 of Fig. 3. Fig. 8 is a view similar to Fig. 7 showing the transparent 75 window moved down, and Fig. 9 is a detail section on the line 9—9 of Fig. 2.

In the practical arrangement of my improved life saving suit the main or body portion of the suit is made of suitable non-sinkable water proof material and includes sleeves 1 having closed ends 2, a body part 3, and leg portions 4 having closed ends 5. The upper or head portion consists of two sections 6—6 adapted to be spread apart, 80 said parts forming, as is were, jaws, large enough, when opened out, to permit of pulling the garment up over the largest person, and of such length, relatively to the head portion of the user, that they can be 85 closed over the head of the user after the garment or suit has been put over the clothing usually worn. The jaws or upper sections 6—6 are secured at their sides and upper ends to a $\square$ shaped steel frame 90 comprised of two sections 8—8 hinged at the lower ends as at 7, and having their opposing edges so beveled that one of the sections 8, can be closed, water tight, within the other section, the said beveled or clamping edges being suitably padded, as at 9 to 95 effect the said water tight closure, see Fig. 4.

In one of the sections 8 is located a port hole 10, having a transparent cover 11, see 100 Fig. 6, so arranged that it may be readily adjusted to the open or closed position by the user within the garment.

12 designates a pair of cam shaped clamp levers mounted on the upper cross member 110 of one of the shaped sections, and relatively so arranged, with respect to a pair of hooks

13—13 projected inwardly from the adjacent member of the other section 8, that the user within the garment can readily move the clamp levers 12 into a locked engagement with the said hooks 13, after he has swung the head sections to their closed position.

14 designates a life preserver, in the nature of an air belt that is attached to the 10 garment around the body portion thereof as shown and the said belt has a valved inlet 15 on the outside for filling it and a similar inlet 16 that projects through the body of the garment to thereby allow the 15 user within the suit, to inflate the belt.

17 designate pockets within the garment for storing fresh water, eatables, an air pump and such other articles as will aid in keeping the user, in case he has to stay afloat 25 an extended length of time.

By reason of the peculiar construction of my life saving garment, the same, when not in use, when the life belt is deflated, may be readily packed, and stored in a trunk 25 with other baggage. When necessity for the use of the garment arises, the belt can be quickly inflated, and with the upper part or jaws spread apart, the user can quickly apply the garment by pulling it up over 30 the body, and when on the user can, working the hands on the inside of the garment, effect the water tight locking of the steel frame jaws, it being understood the port hole is also closed. When thus applied, the 35 user can drop or dive into the water and as soon as he rises to the upright position with the head above the water, the port hole can be opened to admit air and when in calm water, he can open up the head section and stay afloat with the head exposed, 40 which gives him an additional convenience

since the head is not confined within the garment.

The pockets within the garment may be large enough for storing sufficient water 45 and foodstuffs to keep the user alive for days and by reason of the free inflow of air to the upper end of the garment, the user can, as conditions may require, reinflate the life belt from within the garment. 50

The advantage of my improved life saving garment over other like garments heretofore provided, is the simplicity of construction, the ease in which it can be applied by the user without assistance from 55 others and the provision made for entirely exposing the head under conditions that will admit of opening the top ports without danger of shipping water.

What I claim is:

A life saving garment of non-sinkable waterproof material comprising a body portion, leg and arm members closed at their ends, an inflated belt-like portion that surrounds the body, a head portion formed of 65 two opposing sections hinged to open out like a pair of jaws, a port hole in one of the said sections, stiffening elements on the edge of the said opposing sections, said stiffening elements consisting of a pair of 70 $\square$ shaped steel frames hingedly connected at their lower ends, the said frames having beveled edges adapted to close water tight one within the other, cam-like locking levers on the inside of the upper end of one 75 of the $\square$ shaped steel frames and hooks on the other $\square$ shaped steel frames adapted to be engaged by the cam levers, the said cam levers being operable from within the said head portion of the garment when at 80 their closed condition.

BENJAMIN E. HERVEY.
